UNITED STATES PATENT OFFICE.

ELIZABETH COCHRANE SEAMAN, OF NEW YORK, N. Y.

MILK-CAN.

SPECIFICATION forming part of Letters Patent No. 671,150, dated April 2, 1901.

Application filed June 28, 1900. Serial No. 21,887. (No model.)

To all whom it may concern:

Be it known that I, ELIZABETH COCHRANE SEAMAN, a citizen of the United States, residing in the city of New York, borough of Manhattan, in the county of New York and State of New York, have invented certain new and useful Improvements in Milk-Cans, of which the following is a specification.

This invention relates to milk-cans, one object of the invention being to provide a milk-can with an improved reinforced or double neck.

A further object of the invention is to provide an integral breast, neck, and bowl or mouth of a milk-can with a reinforcing neck-band, whereby the neck of such can is reinforced and the can protected and rendered more durable.

In the drawings accompanying and forming part of this specification, Figure 1 is a vertical sectional view of the upper portion of a milk-can, showing one form of this improvement. Fig. 2 is an enlarged sectional view of a portion of the can shown in Fig. 1. Fig. 3 is a vertical sectional view of the upper portion of a milk-can, showing another form of this improvement. Fig. 4 is an enlarged sectional view of a portion of the can shown in Fig. 3. Fig. 5 is a vertical sectional view of the upper portion of a milk-can, showing another form of this improvement. Fig. 6 is an enlarged sectional view of a portion of the can shown in Fig. 5. Fig. 7 is a vertical sectional view of the upper portion of a milk-can, showing an integral breast, neck, and bowl, to the neck of which this improved reinforcing-band is applied. Fig. 8 is a perspective view of one form of reinforcing neck-band; and Fig. 9 is a sectional view of that form of neck-band shown in Figs. 3, 4, 5, and 6.

Similar characters of reference designate corresponding parts in the different figures of the drawings.

It is not only desirable but it is necessary that milk-cans, in order to render them durable and prolong the life thereof to a reasonable extent, shall have their necks protected from injury and reinforced in such a manner that in handling the bending of the necks or the crushing of the bowls upon the breasts and the consequent distortion of such necks will be prevented. When the neck of a can is

bent, twisted, or distorted, not only is it impossible to secure a tight fit of the cover within the mouth of the can, resulting in the overflowing and leakage of the contents, while also permitting the penetration of dust and particles of dirt through the imperfect joint between the cover and the can-neck, thereby affecting the purity of the milk, but the keeping of the can in a proper cleansed condition is interfered with and rendered extremely difficult. Consequently it is necessary that the can be sent to the factory to be repaired, which, however, is not always possible, in which event the life of the can is ended, although it may otherwise be in good condition. Furthermore, it is desirable and a material advantage that the bowl or mouth, neck, and breast be formed integral or in one piece, and therefore seamless, since a better and stronger article, as well as one which is more readily cleansed, can be produced at much less cost than when formed of a number of pieces; but to do this it is necessary, in order to provide a practicable and commercially-successful article, to, in some practicable and inexpensive manner, reinforce the neck, which is a point of great weakness, not only owing to the flexure of the metal at the junction-points of the bowl and breast with the neck, but also owing to the fact that considerable strain must necessarily come upon the neck in the handling of the can, this neck being, when integral with the breast and bowl, merely a straight piece of metal of a single thickness. The bowl and breast are of arched formation, thus increasing their resisting qualities; but the neck is straight to permit the proper fitting of the cover, and it having been drawn out from a disk is consequently somewhat elastic, so that it is easily twisted out of shape, such elasticity also permitting the metal of the neck to spring, and thus permit the can-covers to jar out.

I am aware that it is not new to make a bowl, neck, and breast and a portion of the body of a milk-can of one integral structure; but in the structure to which I refer the defects and disadvantages just pointed out are present, since the neck is not reinforced, so that when the can is used the neck quickly becomes bent or twisted out of shape and the bowl jammed or crushed at one side upon the

breast. In the present instance the bowl or mouth, neck, and breast only are formed as an integral structure, which is, as above stated, a desirable feature, provided the neck is reinforced.

Various ways have been devised to provide a reinforced neck and to which I will briefly refer, so far as I am aware of the same, in order that a clear understanding may be had of the present improvement. In the first place, and so far as I am aware, a milk-can comprising an integral mouth or bowl, neck, and breast or an integral bowl or mouth, neck, breast, and a portion or all of the body has never been reinforced prior to my invention in any practicable manner or by the provision of a reinforcing-band applied either during the formation of such bowl, neck, and breast or after the same is formed, since so far as the market has ever shown the provision of an integral bowl, neck, and breast combined with a band forming a double neck has not heretofore been deemed a practicable possibility. On the contrary, in order to reinforce the neck it has been deemed necessary heretofore to form the bowl and breast separate from each other and furnish each with a neck portion, one overlapping the other and soldered together, thereby providing a double neck, one part, however, formed as a part of the bowl and the other as a part of the breast and depending for their durable connection upon a thin layer of soldering or tinning material; but in all such constructions in order to secure a double neck it is necessary to form the bowl and the breast as separate members, so that the advantages of providing an integral bowl, neck, and breast are not obtained. In another construction of which I am aware the bowl and breast have been formed as separate members connected by a pair of independent neck-pieces, one on the interior and the other on the exterior; but in this construction also the advantages obtained by forming the breast, neck, and bowl as an integral structure must be dispensed with. In still another structure with which I am familiar the neck is bent to form screw-threads for the reception of the cover, and consequently does not present a smooth surface. Externally around these threads may be disposed an extra strip, which, however, owing to the fact that the neck is not smooth, does not engage throughout its entire area the neck of the can, so that it would not be materially effective in reinforcing such neck. The flexure of the metal of the neck in order to provide the threads also increases the tendency of the neck to be crushed or bent out of shape, since the fibers of the metal have already been bent and strained to provide the threads, and as this extra strip when used merely engages the projecting surface of the threads, and therefore does not engage the neck-surface throughout the entire area of the strip, it is consequently held away from portions of the neck, thus interfering with its effectiveness.

In the present improvement the reinforcing-band 2, which can be applied either during the formation of the upper portion of the can, which may be formed by drawing and spinning or otherwise, or applied after the upper portion of the can is otherwise formed, which latter is preferable, since it is more practicable, engages the neck 3, which is shown having a smooth surface throughout the entire area of the band and preferably throughout the entire area of the neck, whereby it has a close engagement at all points with such neck, thus bringing its edges in the preferred form in position at the points of flexure of the breast and bowl, so as to receive any strain or force applied through the bowl or mouth to the neck, whereby it acts not only to stiffen and reinforce such neck, but also as a brace or support for the bowl. When the band is applied before the bowl is spun out, it may be of an integral structure, if desired. As a matter of fact, however, the threaded neck of the patented structure above referred to is not an integral structure or integral with the bowl and breast, since I state that my milk-can is of the ordinary or any suitable construction, and the ordinary construction at the date of the patent was not an integral neck, bowl, and breast. In fact, until some years later the provision of an integral bowl, breast, and neck, which, however, had a portion of the body also integral with such breast, was not believed possible. Moreover, I state that the threads are formed by stamping the strip from which the walls of the neck are formed "previous to soldering it into cylindrical shape," so that not only are the edges of the neck soldered together, but the neck is evidently also soldered or otherwise joined to the bowl and breast after such edges are secured together, since this was the ordinary mode of construction at the time such improvement was made. In the form thereof herein shown and described the bowl 4, neck 3, and breast 5 are formed as an integral structure, the breast being offset adjacent to its lower edge, as at 6, to provide for the reception of the upper portion of the can-body 7. It is obvious that a reverse of this structure could be provided, if desired, so that the bowl could be inserted into the body. The bowl may be of any suitable construction. For instance, it may have greater or less curvature than that shown or curved in a different direction to provide a suitable mouth at the upper end of the neck; any such formation being within the scope of the claims. In practice the breast, neck, and bowl are formed from a disk, such disk being subjected to suitable drawing or stamping operations to form the breast with a straight portion projecting therefrom, the top of which is cut off, after which such straight portion is subjected to a suitable spinning operation to form the neck and bowl. After the breast, bowl, and neck have been formed the reinforcing neck-band 2 is applied either to the

interior or exterior, as found desirable, the ends of which band may be overlapped and soldered or otherwise secured in position. As shown, each end of the band is bent upon itself to provide a hook 12 in engagement with each other, whereby the tight drawing of the band around the neck is permitted and whereby also the band is maintained in its proper position. In the form shown in Figs. 1 and 2 this band 2 is located exteriorly of the neck and in close engagement throughout its entire area with such neck, whereby its upper and lower edges are in position at the points of flexure of the bowl and breast. Thus this band not only reinforces and stiffens the neck to prevent the bending and twisting thereof, but also reinforces the structure at one of its weakest points—namely, where the metal is bent at the edges of the neck. It also acts as a brace to support the bowl and prevent the collapse thereof, as well as enables the neck to resist the strain usually transmitted from the bowl to the neck. In practice the edges 8 of the band may be slightly beveled, whereby it will more tightly fit around the neck intermediate the bowl and breast and closely engage such neck and also the bowl and breast. In another form thereof (shown in Figs. 3 and 4) this band 2' is flanged or bent at its upper and lower edges, although one edge only could be bent, while the other could be formed as shown, for instance, in Fig. 1, if found desirable, such flanges 9 preferably conforming to the shape of the bowl and breast, whereby they constitute beveled surfaces and insure a close engagement of all parts of the band with the neck, bowl, and breast. By this flanged construction of the band not only is the intermediate portion of such band itself reinforced, since it is obvious that a circular band provided with bent edges has greater resisting qualities than a mere straight band, but such flaring or bent edges 9 also reinforce the bowl and breast by not only providing a double thickness of metal 10 at one side of the points of flexure of such bowl and breast, but also by extending the points of engagement of the band with the bowl and breast. In the form shown in Figs. 5 and 6 this improved neck-band 2' is also provided with flanged or bent edges; but the band is, however, located on the interior of the neck. The band may, if desired, have its flanged edges scarfed or beveled, so that they will merge into the surface of the bowl and breast and more closely conform to the shape thereof. This may also be the case with the band shown in Figs. 3 and 4. After the neck-band is placed in position with its ends in locked engagement it is more firmly secured by soldering or tinning material. By the above construction an improved double neck is provided having all the advantages and benefits of such a structure, while at the same time the bowl, neck, and breast can be formed as an integral structure, thus securing all the

advantages of this formation. This reinforcing-band could also be used in practice with those constructions of milk-cans where the bowl and breast are connected together by slip or otherwise formed joints; but by its provision it will permit the manufacture of an integral bowl, breast, and neck which heretofore has not been practicable or a commercial success owing to the weakness of the structure at the neck thereof. When the band is located on the exterior of the neck, which is the preferable construction, the breast, neck, and bowl of the can on the interior thereof may have a smooth and seamless surface, so that there is no crevice into which impure or foul particles of milk or other matter will find lodgment. Consequently the contents of such can will not be affected, it being well known that a drop of foul milk will render impure many gallons during even a short railroad journey. By forming the can seamless on its interior the thorough cleansing of the same is also obtained. By the provision of a suitable reinforcing device located on the neck the twisting of the neck and the springing of the metal thereof is prevented, so that the covers will not work loose. 95

I claim as my invention—

1. A milk-can having an integral breast, neck, and bowl or mouth whereby the interior of such structure is without lapping or other seam and therefore can be readily cleansed, and a reinforcing neck-band drawn tightly around and in engagement with the neck of said integral structure throughout the entire area of said band and also throughout the entire area of said neck and having portions thereof in engagement with the bowl and breast adjacent to the points of flexure of said bowl and breast with the neck. 100 105

2. A milk-can having a breast, neck, and bowl or mouth of an integral structure whereby the interior of such structure is without lapping or other seam and therefore can be readily cleansed, and a reinforcing neck-band located around and in engagement with the neck of such integrally-joined structure 110 throughout the entire area of said band and having beveled portions in engagement with the bowl and breast adjacent to the points of flexure of said bowl and breast with the neck. 115

3. A milk-can having a double neck comprising a neck member integral with the breast and mouth or bowl whereby a seamless inner surface is provided, and a reinforcing neck-band in engagement with said neck member throughout such part thereof and of such width as to prevent the twisting or springing of such neck. 120 125

4. A milk-can having an integral breast, neck, and bowl or mouth whereby the interior of such structure is without lapping or other seam and can therefore be readily cleansed, and a reinforcing neck-band located around and in engagement with the neck of such integrally-joined structure and having 130

portions in engagement with the breast adjacent to the points of flexure of said bowl and breast with the neck and also having its ends interlocked or hooked into each other.

5. A milk-can having an integral breast, neck, and bowl or mouth whereby a seamless inner surface is provided so that such part of the can can be readily cleansed, and a reinforcing neck-band located around said neck throughout substantially the entire area of said neck and having its ends interlocked.

6. A milk-can having a breast, neck, and bowl or mouth of an integral or rigid structure, and a reinforcing neck-band forming 15 with said integral or rigid neck a double neck and provided with a bent or flanged portion in engagement with the bowl or breast.

7. A milk-can having a double neck comprising a neck member integral with the breast and mouth or bowl whereby it has a smooth interior surface and whereby the bowl, breast, and neck are without lapping or other seam 20

to interfere with the cleansing thereof, and a reinforcing neck-band in engagement with said neck member and having a pair of bent 25 or flanged portions.

8. A milk-can having a breast, neck, and bowl or mouth of an integral or rigid structure, and a reinforcing neck-band extending around said integral neck and forming therewith a double neck and provided with a pair of outwardly-turned portions or flanges in engagement with the breast and bowl. 30

9. A milk-can having an integral breast, neck, and bowl or mouth whereby a seamless 35 inner surface is provided so that such part of the can can be readily cleansed, and a reinforcing neck-band located around said neck throughout substantially the entire area thereof.
